VACUUM PUMP

August P. Colaiaco, Pittsburgh, Pa., and Dwight L. Hopper, Jacksonville, Ill., assignors to Westinghouse Electric Corporation, East Pittsburgh, Pa., a corporation of Pennsylvania

Application May 28, 1949, Serial No. 95,938

1 Claim. (Cl. 230—101)

1

Our invention relates to a vacuum pump, and particularly to an oil diffusion pump having high pumping speeds against high back pressure.

In conventional designs of vapor pumps, high speed has been obtained by having a first stage with a large pumping radius (the pumping radius being the distance between the edge of the first stage jet and the inside wall of the pump barrel), and decreasing the pumping radius of each successive stage to produce a decrease of pumping radii from the intake to the exhaust end of the pump. Heretofore, this decrease of pumping radii has been obtained by using a substantially uniform diameter pump barrel and increasing the diameter of the pumping stages from the first or intake to the last or exhaust end of the barrel.

While this gives a relatively small pumping radii, the large area involved causes a dispersion of the vapor so that back streaming of the gas through the pumping vapor is of material quantity. Consequently, these high speed pumps will not exhaust against a high back pressure and it is accordingly customary to use a booster pump to increase the exhaust pressure so that a secondary or mechanical vacuum pump will be efficient in discharging the pumped gases.

According to our invention, we have provided a diffusion pump having high pumping speeds and capable of exhausting against high back pressures, so that a booster pump may be dispensed with.

In a construction according to our invention, each of the pumping jets or stages is of substantially uniform diameter and the pump barrel is substantially frustoconical converging from a large intake opening to a relatively small exhaust opening. By this manner, the large pumping radii of the first stage is obtained and the small pumping radii of the last stage is obtained, but with the additional advantage that the cross sectional area of the exhaust stage is relatively small, so that almost no back streaming results and the pump therefore will operate against the high back pressures normal for booster pumps.

It is possible and practical to fit a small spinning into a small opening with much smaller tolerances than are required when fitting large spinnings into large openings. Consequently, in a pump according to our construction, the pumping radii and the exhaust area can be made much smaller and precise than in the heretofore conventional type pumps.

In the conventional pumps having a plurality of pumping jets fed from a single vapor chimney, starvation of the jets farthest removed from the

2

source of vapor has frequently been observed. This starvation results primarily from the exhaustion of the gas by its being utilized by the jets nearest the source of vapor or by cooling which reduces the volume of the vapor. We have found that by introducing the vapor from the pump intermediate the jets, the vapor reaches all of the jets at substantially the same pressure, thus materially increasing the effectiveness of the pump. When it is desired to distribute the pressure in some particular order the vapor inlet may be shifted to introduce the vapor at or near the point where the highest pumping pressure is desired.

15 In order to provide a relatively short distance from the boiler or other source of vapor to the pumping chimney, we provide a horizontal pump with a boiler attached adjacent the mid portion of the pump, so that a relatively short vapor passage connects the boiler to an intermediate portion of the chimney.

20 It is accordingly an object of our invention to provide a high speed, high pressure vacuum pump.

25 It is a further object of our invention to provide a vacuum pump in which the pumping area decreases from the intake to the exhaust end of the pump.

30 It is a further object of our invention to provide a vapor pump having substantially uniform or controlled vapor pressures to all pumping jets.

35 Other objects and advantages of our invention will be apparent from the following detailed description taken in conjunction with the accompanying drawing, in which the figure is a sectional elevation of a vapor condensation pump according to our invention.

40 In the exemplary embodiment of our invention, a vapor diffusion pump comprises a substantially frustoconical body or barrel portion 10 having cooling coils 11 applied to the exterior surface thereof so that the interior surface 12 of the barrel 10 is a cooling surface for the pumping vapors. Substantially axially arranged in 45 the pumping barrel is a chimney or supply pipe 15 on which is arranged a plurality of pumping jets 16. Preferably, these jets 16 are substantially uniform in diameter, so that each of the spinnings, except the initial stage 16', can be identical spinnings.

45 Usually it is preferred to provide the initial spinning 16' in the form of a cap 17 substantially closing the initial end of the vapor chimney 15, but obviously the first stage 16' can be exactly like all of the other stages and the cap either

dispensed with or provided as a portion of the chimney 15. The larger intake end 18 of the pump barrel 10 is connected to the space 19 to be evacuated and the smaller or exhaust end 20 of the barrel 10 is connected to any sort of secondary vacuum pump.

A boiler 21 is attached to the pump adjacent the central portion thereof and has a vapor tube 22 extending from the boiler 21 to a junction 23 with the chimney 15 substantially adjacent the mid portion thereof or at least intermediate the ends of the chimney 15 and between the pumping stages 16.

In order to prevent cooling of the vapor between the boiler 21 and the pumping chimney 15, a plurality of concentric tubes or shields 24 and 25 are placed around the vapor passage 22 and are open to the interior of the pump, so that a low pressure will be maintained in the space between the concentric tubes 24-25 and the vapor passage 22. Preferably the portions of the chimney 15 are mounted on and supported by the vapor tube 22 so that different types of pumps may be constructed by simply screwing in portions of the chimney 15 having the desired pumping jets 16. In order to return condensed pumping material to the boiler 21, a return pipe 26 is provided from adjacent the large end 18 of the barrel 10 to a point adjacent the bottom of the boiler 21. Usually some sort of barrier 27 is provided to prevent condensed pumping fluid passing the inlet port of the return tube.

While any sort of heating device may be utilized for the boiler, we prefer to provide an electric heater 28 either immersed in the oil or attached in good thermal relation to the external portion of the boiler 21. Any suitable thermal insulation, not shown, may be applied to the boiler 21 or the exposed portion of the heat conserving concentric tubes 24.

In the operation of the pump according to our invention, the large end 18 is attached to the space 19 to be evacuated and the exhaust end 20 to any suitable vacuum pump and heat is applied to the boiler 21 to produce a flow of vapor into the chimney 15 and from the chimney 15 through the pumping jets 16. The pumping vapor entrains molecules of gas and causes them to move from the intake to the exhaust end of the pump so that a very low pressure will be maintained at the intake and a higher pressure at the exhaust end of the device.

The pumping vapor impinges on the cooled condensing surfaces 12 and is condensed and returns to the boiler 21 to be recycled. When the pump is to be utilized to exhaust against an unusually high pressure, the exhaust stage 16 should be sufficiently close to the exhaust end 20 of the barrel 10 that a very short pumping radii is established having a very small effective cross sectional area so that back streaming is substantially eliminated.

While for purposes of illustration we have shown and described a preferred embodiment of our invention and described the same to the best of our present ability, we wish it to be understood that changes and modifications can be made therein without departing from the true spirit of our invention or the scope of the appended claim.

We claim as our invention:

1. A vapor pump comprising means for providing a tapering chamber, cooling means applied to said chamber to produce a condensing surface therein, a vapor supply pipe of substantially uniform diameter from end to end, located substantially centrally within said chamber, said supply pipe having an end-structure at each end, a plurality of diffusion jets of substantially uniform diameter connected to said vapor supply pipe at spaced points along its length, said jets being directed to move gas from the large to the small end of said chamber, a boiler for producing pumping vapor, and connection-means for supplying vapor from said boiler to said vapor supply pipe, said connection-means being at a point intermediate the ends of the vapor supply pipe.
